(57) CLAIM

The ornamental design for a golf bag dual shoulder strap, as shown and described.

DESCRIPTION

FIG. 1 is a perspective view of a golf bag dual shoulder strap according to the new design;

FIG. 2 is a left side view of the golf bag dual shoulder strap according to the design;

FIG. 3 is a front view of the golf bag dual shoulder strap according to the design;

FIG. 4 is a right side view of the golf bag dual shoulder strap according to the design;

FIG. 5 is a bottom view of the golf bag dual shoulder strap according to the design;

FIG. 6 is a rear view of the golf bag dual shoulder strap according to the design; and,

FIG. 7 is a top view of the dual golf shoulder strap according to the design.

In the drawings, short light broken lines depicting the connectors located at each end of the straps form no part of the claimed design. The long, heavy lines represent stitching and are part of the claimed design. In FIGS. 1-7 portions of the straps are shown broken away and set-off by brackets and wave-like lines. The appearance of any portion of the article between the wave-like break lines forms no part of the claimed design. Any contrast in color intensity or darkness as between stippling shown in the central portion of the shoulder strap versus stippling in the other regions of the strap represents a contrast in appearance there between.
